US0D1097441S

(12) **United States Design Patent** (10) **Patent No.:** **US D1,097,441 S**
(45) **Date of Patent:** **** Oct. 7, 2025**

(54) **LOCK BOX**

(71) Applicant: **Vaultek Safe Inc.**, Altamonte Springs, FL (US)

(72) Inventor: **Dustin Thomas Culbreth**, Savannah, GA (US)

(73) Assignee: **Vaultek Safe Inc.**, Altamonte Springs, FL (US)

(**) Term: **15 Years**

(21) Appl. No.: **29/905,261**

(22) Filed: **Oct. 18, 2023**

(51) LOC (15) Cl. **99-00**

(52) U.S. Cl. **D99/28**
USPC ....
